US00D997902S

(12) **United States Design Patent** (10) **Patent No.:** **US D997,902 S**
(45) **Date of Patent:** **** Sep. 5, 2023**

(54) **SPEAKER**

(71) Applicant: **HEWLETT-PACKARD DEVELOPMENT COMPANY, L.P.**,
Spring, TX (US)

(72) Inventors: **David Quijano**, Spring, TX (US);
Stacy L. Wolff, Spring, TX (US);
Owen P. Columbus, Spring, TX (US);
Paul L. Drew, Spring, TX (US);
Marcus Hoggarth, London (GB); **Cian Plumbe**, London (GB); **Seong Min Hwang**, London (GB); **Ben Henley**, London (GB); **Benjamin Keep**, London (GB); **Jainel Shah**, London (GB)

(73) Assignee: **Hewlett-Packard Development Company, L.P.**, Spring, TX (US)

(**) Term: **15 Years**

(21) Appl. No.: **29/807,755**

(22) Filed: **Sep. 14, 2021**

(51) LOC (14) Cl. **14-01**

(52) U.S. Cl.

USPC **D14/214**

(57) **CLAIM**

The ornamental design for a speaker, as shown and
described.

DESCRIPTION

FIG. 1 is a perspective view of a speaker in an open position
in accordance with the new design;

FIG. 2 is a front view of the speaker of FIG. 1;

FIG. 3 is a back view of the speaker of FIG. 1;

FIG. 4 is a left side view of the speaker of FIG. 1;

FIG. 5 is a right side view of the speaker of FIG. 1;

FIG. 6 is a top view of the speaker of FIG. 1;

FIG. 7 is a bottom view of the speaker of FIG. 1; and,

FIG. 8 is a front view of the speaker of FIG. 1 in a closed
position.

The dot-dash broken lines immediately adjacent to the
claimed areas in the views represent the boundaries of the
design and form no part thereof.

None of the broken lines form any part of the claimed
design.

1 Claim, 5 Drawing Sheets
